United States Patent Office

Des. 221,925

Patented Sept. 21, 1971

221,925

COMBINED SHEARS AND MEASURING RULE

Walter K. Fogg, 45 Kensington St.,
Feeding Hills, Mass. 01030

Filed June 3, 1970, Ser. No. 23,291

Term of patent 14 years

Int. Cl. D8—03

U.S. Cl. D8—55

FIG. 1 is a top perspective view of a combined shears and measuring rule showing my new design; and

FIG. 2 is a perspective view with the article in inverted position.

I claim:

The ornamental design for combined shears and measuring rule, as shown.
